SAFETY CLOTHES WRINGER

Walter L. Kauffman, 2d, Youngstown, Ohio

Application June 19, 1930. Serial No. 462,282

3 Claims. (CL. 68—32)

This invention relates to clothes wringers.

The principal object of this invention is to provide a wringer that is absolutely safe in operating, inexpensive of manufacture, and efficient.

5 A further object of the invention is to provide a wringer hung in a pivoted manner so that a pull or a push against the wringer will automatically release pressure exerted on the rolls of the wringer and disengage a drive shaft actuating 10 one of the rolls of the wringer.

In the ordinary construction of wringers safety devices have been attached thereto, those operating upon the plan of utilizing a lever or a latch to release or disengage the transmission actuating 15 rollers, etc. The danger comes in that an operator of a wringer might have both hands engaged and both hands caught in the wringer leaving no opportunity to actuate the safety devices common to wringers. Again the person operating the 20 wringer may become confused due to the pain subjected to either hand that might be in the wringer or hair of the operator and thus momentarily cause inaction on the part of the operator until serious damage has been done by a continuation 25 of the rolls of the wringer.

In my improved wringer, I have utilized the principle of self preservation which individuals use subconsciously when in or approaching danger. The average individual would naturally 30 and instantly try to withdraw the hand or hands from the wringer as soon as discovered. This would cause the wringer to swing upon its pivot and automatically disengage the pressure on the rolls and also disengage a transmission actuating 35 the movement of the rolls.

With the foregoing and other objects in view which will appear as the description proceeds, the invention resides in the combination and arrangement of parts and in the details of construction 40 hereinafter described and claimed, it being understood that changes in the precise embodiment of the invention herein disclosed, can be made within the scope of what is claimed, without departing from the spirit of the invention.

45 The invention is illustrated in the accompanying drawing, wherein:—

Figure 1 is a front elevation of the device with parts broken away.

Figure 2 is a partial top plan view of Fig. 1.

50 Figure 3 is a cross section taken on line 3—3 of Fig. 1.

By referring to the drawing it will be seen that the wringer frame consists of a lower member 1, end uprights 15, and a casing 12. The wringer frame is pivotally connected to a bracket member

2 by means of pivot lugs 3 which pass through support members 4 of the wringer 1 and into the bracket member 2. Rolls 5 and 6 are mounted in bearings in these uprights 15. The wringer roll 5 is caused to revolve by means of a power shaft 7 60 which is empowered by means of standard gears within a gear casing 8. This gear casing 8 carries the bracket 2.

It will be seen that the roller 6 is caused to revolve by frictional contact with roller 5, or by 65 frictional contact with articles being put through the rollers 5 and 6. The roll 6 is held under tension by means of a spring 9 which may be adjusted by means of an adjustment screw 10 by operating an operating member 11. It will be 70 seen by referring to the drawing that the screw 10 is vertically adjustable relative to the casing 12 and relative movement is permitted between the screw 10, spring 9, and the upper wringer roll bearings. This adjustment screw 10 is centrally located and functions with a casing 12. The outer ends of this casing 12 are provided with engaging pins 14. By referring to Figure 1 it will be seen that there is provided vertical outer frame members 15 and each frame member 15 is 75 80 provided with an angular slot 16 at its upper end.

By referring to Fig. 1 it will be seen that the left turn portion of the angular slots 16 provides a latch seat for the engaging pins 14.

By referring to Figure 2 it will be seen that the 85 casing 12 is provided with oppositely disposed projections 17 which function with oppositely disposed shoulders 18 which are carried at the upper part of the bracket member 2. It will be seen that if the operator's fingers become engaged between the rollers 5 and 6, the operator will instinctively pull in an effort to disengage the fingers. One of the oppositely disposed projections 17 will swing against the shoulder 18 and cause the casing 12 to be slid so that the engaging pins 14 will be carried free from the latch seat of the angular slot 16 and allowed to travel upwardly through the upper portion of the angular slots 16 thereby releasing pressure upon the rolls 6. 90 95

100 It will also be seen that the same action will take place no matter if the wringer is swung back or forward upon the pivot lugs 3. It will also be seen that the shaft 7 is joined at a point 19 by means of a plurality of parallel ridges and depressions thereby forming a clutch medium. It will be seen that when the wringer 1 has been swung backward or forward the shaft portion carried by the wringer will be carried out of engagement with the empowered portion of the 105 110

shaft 7 and thereby disconnect power transmission to the wringer. The casing 12 has an open bottom and encloses spring 9 and is adapted to be released from and locked to the upper ends 5 of uprights 15. Near the ends of casing 12 are provided transversely extending pins 14 for releasably engaging a holding means on the uprights. The upper portion of the slot in an upright is vertical and the lower part is horizontal, 10 the horizontal portions of the slots extending in the same direction away from the vertical portions. Shaft 7 is formed of two aligned sections, one section being carried by the wringer frame and the other by the bracket. Point 19 is outside 15 of the axis of pivot lugs 3 and is between the bracket 2 and the adjacent upright 15. The axis of the pivot lugs lies in the plane passing through the axis of the wringer rolls.

What I claim is:—

- 20 1. In a device of the class described, a wringer including a frame and having rolls mounted in said frame, vertically spaced support members formed on one end of said frame, a supporting bracket, pivot lugs passing through said support members and secured to said bracket, means for releasing tension upon the wringer rolls by moving the wringer backward or forward in an arc about the axis of said pivot lugs, the axis of said lugs lying in the plane passing through 25 the axes of said rolls, a rotary shaft extending through said supporting bracket and into said frame for transmitting power to one of said rolls, said shaft being formed in two aligned sections each having a plurality of parallel ridges and 30 depressions formed on the joined ends of said rotary shaft for the purpose of forming a clutch, one of said sections being mounted in said supporting bracket and the other of said sections being mounted in said frame and said joined ends 35 being between said frame and the axis of said pivot lugs whereby the sections of said rotary shaft may be disengaged by swinging said wringer backward or forward about the axis of said pivot lugs.
- 40 2. In a device of the class described, a wringer including a frame, and having rolls mounted in said frame, vertically spaced support members formed on one end of said frame, a supporting bracket, pivot lugs passing through said support 45 members and secured to said bracket, a pair

of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins.

3. In a device of the class described, a wringer including a frame and having rolls mounted in said frame, vertically spaced support members formed on one end of said frame, a supporting bracket, pivot lugs passing through said support members and secured to said bracket, a pair of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins. 90

3. In a device of the class described, a wringer including a frame and having rolls mounted in said frame, vertically spaced support members formed on one end of said frame, a supporting bracket, pivot lugs passing through said support members and secured to said bracket, a pair of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins. 95

3. In a device of the class described, a wringer including a frame and having rolls mounted in said frame, vertically spaced support members formed on one end of said frame, a supporting bracket, pivot lugs passing through said support members and secured to said bracket, a pair of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins. 100

3. In a device of the class described, a wringer including a frame and having rolls mounted in said frame, vertically spaced support members formed on one end of said frame, a supporting bracket, pivot lugs passing through said support members and secured to said bracket, a pair of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins. 105

3. In a device of the class described, a wringer including a frame and having rolls mounted in said frame, vertically spaced support members formed on one end of said frame, a supporting bracket, pivot lugs passing through said support members and secured to said bracket, a pair of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins. 110

3. In a device of the class described, a wringer including a frame and having rolls mounted in said frame, vertically spaced support members formed on one end of said frame, a supporting bracket, pivot lugs passing through said support members and secured to said bracket, a pair of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins. 115

3. In a device of the class described, a wringer including a frame and having rolls mounted in said frame, vertically spaced support members formed on one end of said frame, a supporting bracket, pivot lugs passing through said support members and secured to said bracket, a pair of oppositely disposed shoulders formed on said bracket, a casing member having an open bottom and extending between the upper ends of the uprights of the wringer frame, engaging pins carried at outer ends of said casing member, a pair of oppositely disposed projections carried on the casing for engaging one or the other of said oppositely disposed shoulders carried on the bracket, angular slots formed in said uprights positioned so as to have a vertical and horizontal portion, the horizontal portions of the slots extending in the same direction from the vertical portions in the uprights in order to form a latch seat for the reception of said engaging pins. 120
